UNITED STATES PATENT OFFICE.

JOHN I. IBLINGS, OF CEDAR FALLS, IOWA.

SNOW-FENCE.

1,026,806.

Specification of Letters Patent.

Patented May 21, 1912.

Application filed May 25, 1911. Serial No. 629,406.

To all whom it may concern:

Be it known that I, JOHN I. IBLINGS, a citizen of the United States of America, and a resident of Cedar Falls, Blackhawk county, 5 Iowa, have invented certain new and useful Improvements in Snow-Fences, of which the following is a specification.

My invention relates to improvements in snow fences, and the object of my improvement is to provide a foldable, knock-down fence, preferably formed of metal, and which has special means for securing it to the ground, and is convenient, durable and easily set up or transported. This object I have 10 accomplished by the means which are herein-after described and claimed, and which are illustrated in the accompanying drawings, in which:

Figure 1 is a perspective view of a section 20 of snow fence constructed according to the principles of my invention, and set up ready for use. Fig. 2 is a perspective detail view of the pivotal foot used to seat the lower end of the brace of the fence upright firmly 25 in the ground, and Fig. 3 is a medial longitudinal section of said pivotal foot taken through its U-shaped cut at one side of the turned-up lip.

Similar letters of reference designate 30 corresponding parts throughout the several views.

My improved fence is preferably formed in sections which may be connected end to end in any suitable manner to form a continuous line. Each section is also preferably inclined somewhat toward the earth, as illustrated, and is supported by braces *f*. The fence is constructed of uprights *a*, which may be metal bars, or of angle iron, or of 40 metal of any desired section which may be suitable to the purpose.

The uprights *a* are connected by horizontal superposed metal plates *b*, *i*, *k* and *l* of similar form, but any number of such plates may 45 be employed as desired, or to fill the necessities arising from the nature of the ground. As shown, each plate is of sheet metal, with its upper part curved or bent to present a hollowed upper face, but the curvature of said 50 plates may be such as to present their concave faces toward the earth. This curvature strengthens the plate, but the curve may be of any type or the plates may be bent in a different manner from that shown without 55 departing from the principle of my invention. The ends of the plates may be secured

to the uprights *a* by rivets or bolts *c*. As shown in Fig. 1 the lower end of each upright *a*, as also the lower end of each brace *f* 60 may have an angularly directed foot *d*, integral therewith, which may be secured to the ground by hook-pins *e*. I prefer, however, the means shown in Fig. 2 for securing the uprights and braces to the ground. In said figure the means described and shown 65 are only applied to the brace *f*, but the same means may be applied to the foot of each upright. This latter means comprises a plate of metal *m* which has a U-shaped cut made in its center and the lip *n* then turned up 70 and pivoted at *o* to the lower end of the brace *f*, the latter being shown in Fig. 2 as preferably formed of angle iron. The particular advantage of this means is to plant 75 the plate in the earth, insuring stability, or if the ground is too hard or frozen, hook-pins such as *e* may be driven through the hole in each plate to secure the plate on the ground. The braces *f* are preferably formed, 80 as also the uprights *a*, to conform to the curves of the plates *b*, *i*, *k* and *l*, so that they may fold together in small compass for transportation, and of course, the foot plates *m* may also fold over. The upper ends of 85 the braces *f* are connected pivotally to the upper ends *g* of the uprights by means of pintles *h*.

Since the parts of my improved fence are formed of metal, they will not be damaged 90 by prairie fires, and will also be very enduring against the attacks of the elements, or destruction by boys or animals. The troughed or longitudinally bent form of the plates *b*, *i*, *k* and *l*, lends stiffness to them as it does in other longitudinally bent or arc-shaped trough-like structures, and permits 95 the use of quite thin galvanized iron for the sake of economy and lightness in transportation, without liability of buckling or distortion of the plates. They are thus particularly useful for snow fences along railway 100 lines, though not confined to that purpose, as such a fence may be used anywhere where it is desired or of use.

Having described my invention, what I 105 claim as new, and desire to secure by Letters Patent, is:

1. A fence composed of a plurality of uprights connected by a plurality of superposed metal bars, the bars being longitudinally 110 troughed, braces pivoted to said uprights, said uprights being formed to conform to

the shapes of said bars and said braces being formed to conform to the same shape and adapted to swing toward the uprights, and means for securing both the uprights and the braces to the ground.

2. A fence composed of a plurality of uprights, a plurality of longitudinally curved bars connecting said uprights, braces hinged to the tops of said uprights, both said uprights and braces being of like form and formed to conform to the curvatures of said

bars, and plate-like bodies so pivoted to the bases of said uprights and bars as to be adapted to be embedded substantially horizontally in or placed on the earth for securing said uprights and braces to the earth. 15

Signed at Waterloo, Iowa, this 6th day of May 1911.

JOHN I. IBLINGS.
